JAMES F. MATTHEWS Inventor

By *Richard Oliver* Attorney

UNITED STATES PATENT OFFICE.

JAMES F. MATTHEWS, OF NORTH AUGUSTA, SOUTH CAROLINA, ASSIGNOR OF FIFTY-
ONE ONE-HUNDREDTHS TO WADE H. WHITE, OF AUGUSTA, GEORGIA.

BOX.

Application filed May 6, 1922. Serial No. 559,014.

To all whom it may concern:

Be it known that I, JAMES F. MATTHEWS, a citizen of the United States, residing at North Augusta, in the county of Aiken and State of South Carolina, have invented certain new and useful Improvements in Boxes, of which the following is a specification.

This invention relates to new and useful improvements in boxes, crates and the like, and has for its primary object the provision of adjustable means for varying the interior size of the box and for clamping articles placed therein to prevent their vibration and possible breakage.

Another important object of the invention is to provide a receptacle of the above character having an adjustable bar or partition associated therewith and simple actuating means for the bar or partition arranged so as to be easily manipulated and at the same time disposed in such relation to the receptacle as to be free from accidental movement.

A further object of the invention is to provide an adjustable member as above set forth and resilient means for retaining the member in the desired adjusted position so that the member will be subject to slight movement in order to properly hold the contents of the receptacle against vibration.

A still further object of the invention resides in the provision of a cam actuator for the adjustable member which, when arranged in a position to hold the adjustable member in its adjusted position will not be subject to accidental movement.

Another object of the invention is to provide a movable member of the above character which is constructed so that the same can be deflected for the accommodation of articles of different sizes in the container with which the member is associated.

A still further object of the invention is to provide a simple and inexpensive arrangement for the accomplishment of the above objects which can be applied to boxes, crates and the like which are now in constant use.

Other objects and advantages of the invention will become apparent during the course of the following description.

In the accompanying drawings forming

a part of the description and wherein like numerals are employed to designate like parts throughout the several views,

Figure 1 is a perspective view of a container with the invention applied thereto,

Figure 2 is a transverse section through the same,

Figure 3 is a horizontal section taken on the line 3—3 of Fig. 2,

Figure 4 is a fragmentary transverse section of a container illustrating the preferred adjustable member associated therewith, and

Figure 5 is a fragmentary perspective view of the preferred adjustable member.

In the drawing wherein for the purpose of illustration is shown the embodiments of the invention which are at present preferred, the numeral 6 designates a receptacle such as a box or crate of the type usually employed for transporting glass articles such as bottles containing beverages. This receptacle in the present instances consists of a bottom, a pair of sides 7, and a pair of ends 8, the latter each being provided with a hand hole 9 of any desired configuration for the convenience of those transporting the receptacle. Each end wall 8 of the receptacle is provided in its outer face with recesses 10 extending transversely of the receptacle and from opposite ends of the hand hole 9 therein.

Ordinarily boxes or crates for carrying bottles are provided with a plurality of intersecting partitions so as to form a separate compartment or pocket for each bottle so as to prevent rattling and breakage thereof. The present invention aims to eliminate the expense incident to the provision of a plurality of intersecting partitions heretofore used, secondly to make it possible to construct these types of crates and boxes smaller and at the same time have the same capacity as the partitioned crates, thirdly, to provide means for securely clamping the articles in the receptacle to prevent any possible movement of the receptacles.

These objects are accomplished by the provision of an adjustable member 11 movable relative to one of the walls of the container to vary the interior size thereof. In Figs. 1, 2 and 3 the adjustable member 11 consists of a relatively wide board which

may extend from the bottom of the receptacle to the top edge thereof and from one side 7 to the other. This board is adapted for movement longitudinally of the receptacle or from one end thereof to the other, and in order that this board can be moved in this direction without binding in any way, its vertical side edges are provided adjacent the upper and lower ends 5 thereof with a pair of grooves 12 adapted to receive a pair of spaced parallel ribs 13 carried by the inner faces of the sides 7 of the receptacle. These ribs are parallel to the bottom of the receptacle and as seen in 10 Figs. 1 and 3 extend only a slight distance inwardly of the receptacle from an end 8 thereof. It will of course be obvious that the ribs and grooves may be reversed so that the grooves are provided in the sides 15 20 of the receptacle while the ribs are provided on the edges of the movable member 11.

In order that the adjustable member will be resiliently retained in engagement with 25 articles positioned in the receptacle the relative outer face of the board 11 or the face adjacent the end wall 8 from which the ribs 13 extend is provided with a flat resilient plate or spring 14 arranged to extend transversely 30 of the receptacle and secured at one end by means of a rivet 15 or other suitable means. The other end of the spring 14 is free as shown, and the intermediate portion of the spring is bowed outwardly to extend slightly 35 into the hand hole 9 when the adjustable member is arranged close to the end wall having this hand hole therein.

The means I provide for moving the member 11 toward the center of the receptacle 40 and inwardly thereof, consists of a cam lever 16 having a cam head 17 pivoted within the hand hole 9 of the end of the receptacle adjacent the movable member by means of a vertical bolt or pin 18 extending 45 through the cam head at a point eccentric therein and having its opposite ends journaled in the top and bottom of the hand hole. It will be noted that the nose 19 of the cam head 17 is extended to be arranged 50 between the pivot pin and the handle whereby the cam lever will not be accidentally swung outwardly to release the movable member 11 when it is locked and when pressure is exerted against the movable member 55 by the articles disposed in the container. It will also be noted that the handle of the cam lever is arranged in one of the recesses 10 when the lever is unlocked or in an inoperative position and will be disposed in the 60 other groove or recess 10 when the lever is arranged in a position to hold or force the movable member toward the center of the receptacle.

In Figs. 4 and 5 I have shown the form 65 of movable member 11 which is at present

preferred. This member consists of either a solid or a sectional bar 20, the ends of which are each provided with a horizontal rib 21 adapted to be slidably received in grooves 22 in the sides 7 of the receptacle. 70 These grooves are of course, arranged parallel to the bottom of the receptacle and directly opposite each other so that the board will have free sliding movement therein. The bar in the present instance is shown as consisting of a pair of sections 23 which are slightly separated at their inner ends and connected in such relation by a pair of plates 24 one of which is secured to the relative upper faces of the inner ends of the sections 23, and the other secured to the relative lower faces of the sections as shown. These plates are secured to the sections at each end by a fastening device 25, it being noted that one fastening device is provided 80 for each end of each plate 24 whereby the sections can pivot slightly at their inner ends and conform to one end of articles placed in the receptacle. The spring 14, and cam lever 16 are of course used in conjunction with either a rigid or sectional bar 20 so that the same can be firmly held in engagement with bottles placed in the receptacle to prevent their vibration and rattling 85 against one another. 90

In use, and when it is desired to pack the bottles or other articles in the box, the cam lever is swung so that the edge of the cam head nearest the pivot pin 18 contacts with the spring 14 of the movable member 11 to 100 permit the latter to be pushed close up against the end 8 having the cam lever associated therewith. The bottles or articles are then positioned in the box until it is filled after which the cam lever is swung to move 105 the member 11 into engagement with the ends of the articles disposed adjacent the same. The lever is swung until the nose 19 of the cam head engages the spring 14, and the handle of the lever is disposed in its 110 proper groove or recess 10. By the interposition of the spring between the cam and the movable member means is provided whereby the latter may properly adapt itself to and engage the articles in the container. 115 With the cam lever in either one of its extreme positions, it will be seen that the fingers of the person intending to transport the receptacle can be readily inserted into the hand holes in the ordinary manner. When it is desired to move the articles from the container, the cam lever is simply swung to its opposite position to release binding engagement of the movable member upon the articles. 120

The foregoing description and accompanying drawings have reference to what might be considered the approved form of my invention. I desire it to be understood that I may make such changes in the con- 125 130

struction, combination and arrangement of parts, materials, dimensions, etc. as may prove expedient and fall within the scope of the appended claims.

5 Having thus described my invention what I claim is:—

1. A receptacle, a member arranged therein to vary the interior size thereof, and a cam associated with the receptacle and 10 adapted to move the member inwardly thereof.

2. A receptacle having a hand hole in an 15 end thereof, a movable member arranged in the receptacle and having its ends slidably engaged with the sides of the receptacle, a bowed spring secured to said member and arranged opposite said hand hole, and a cam lever pivotally mounted in said hand hole and adapted for engagement with the bowed 20 spring for moving the movable member.

3. In combination with a receptacle, a member arranged therein to vary the interior size thereof, means associated with the box and adapted to move the member inwardly thereof, and spring means disposed 25 between said last mentioned means and said member whereby the spring means will be

flexed when said member engages articles positioned in the receptacle.

4. In combination with a receptacle, a 30 movable member arranged in the receptacle and having its ends slidably engaged with the sides of the receptacle, a cam lever pivotally connected to the receptacle for moving said member, and a bowed spring positioned 35 between said member and the cam lever for the purpose set forth.

5. In combination with a receptacle having an opening in one of its ends and a recess communicating with the opening in 40 the exterior surface of said end, a movable member arranged in the receptacle to vary the interior size thereof, and means associated with said end of the receptacle for moving said member, said means being disposed wholly within said opening and recess.

In testimony whereof I affix my signature in presence of two witnesses.

JAMES F. MATTHEWS.
